Wm. H. Carson & George Roberts. - of York, coⁿ Livingston - New York,

Letters Patent

The Schedule referred to in these Letters Patent and making part of the same, containing a description in the words of the said William H. Carson, and George Roberts themselves of their improvement in the Cement for Cisterns &c.

To all, to whom these Presents may come - Be it known that we William H. Carson & George Roberts of York, county of Livingston and State of New York have invented a new and useful invention, and that the following is a full and exact description thereof. Mix Nine Parts Sand, three parts Waterlime, one part plaster Paris, and one quarter part Muriate of Soda. Mix with water into a cement, to be applied to the surface of holes dug in the earth of any dimension for the purpose of holding water.

What we claim as our own invention and improvement is the addition of the Plaster of Paris and the Muriate of Soda to the other articles -
